Thomte Patent Law Office LLC(57) **CLAIM**

The ornamental design for a wheel guard, as shown and described.

DESCRIPTION

FIG. 1 is a top perspective view of a wheel guard, showing my new design;

FIG. 2 is a bottom perspective view thereof;

FIG. 3 is another top perspective view thereof;

FIG. 4 is a front view thereof;

FIG. 5 is a top view thereof;

FIG. 6 is a side view thereof; and,

FIG. 7 is another side view of the wheel guard shown in its position of use.

In the drawings, the broken lines depict environmental subject matter and form no part of the claimed design.
